UNITED STATES PATENT OFFICE

2,538,498

METHOD AND APPARATUS FOR
DETERMINING TOXICITY

Matthew Edward Benesh, Cicero, Ill.

Application September 3, 1948, Serial No. 50,761

4 Claims. (Cl. 73—23)

1

The present invention relates to testing apparatus and more particularly to a gassing chamber for rapidly determining the toxicity of various fluids. An important object of the present invention is to provide an improved apparatus for the rapid determination of the effect of toxic compounds on animal life. Another object is to provide such apparatus that is capable of testing a greatly increased number of different compounds in a given period of time. A further object is to provide means for the rapid and accurate testing of substances of low volatility. Other equally important objects will more plainly appear from the detailed drawings and specification presented in exemplification but not in limitation of the present invention. Like reference characters represent like parts in the drawings which illustrate diagrammatically in:

Figure 1, a diagram illustrating a preferred arrangement of the various cooperating elements of the apparatus.

Figure 2, a diagram illustrating details of the piston and cylinder and showing a rear view of the burette assembly shown in Figure 1.

Figure 3, a view in perspective of a detail of the carriage assembly.

Prior gassing chambers possessed certain inherent disadvantages among which are the following six serious defects. First, the time consumed. Prior chambers require a period of equilibration to establish the desired concentration before animals can be exposed in it. The equilibration period varies with the rate of air flow through the chamber and can be described by the equation:

$$T_{99} = \frac{4.6 \times \text{chamber volume}}{\text{rate of air flow}}$$

in which T_{99} equals the time required to establish 99% of the desired equilibrium concentration. In the case of the 400 liter chamber operating with an air flow of 250 liters per minute, 7.5 minutes are required for equilibration. For example, a ten minute exposure requires an experimental period of approximately 18 minutes.

Second, the prior art hazards. When equilibrium has been established, the animals are inserted into the chamber, and after the desired period of exposure they are withdrawn. During both of these operations, the rate of flow of the toxic vapor into the gassing chamber cannot be interrupted. However, when the sliding door of the chamber is opened for insertion or removal of the animals, the negative pressure which sucks toxic vapor into the chamber is overcome causing toxic vapor to flow into the laboratory. This

requires the use of a mask by the operators, and in testing powerful sensory irritants unmasked laboratory personnel not in the immediate vicinity of the chamber may be harmed.

Third, the excessive amounts of material required. Since 250 liters of air per minute for approximately 20 minutes pass through prior chambers during the determination of a ten minutes exposure mortality figure, it will be apparent that about 5,000 times the desired concentration in milligram per liter of toxic agent is required for a single determination. Since new agents are often submitted in 10 or 20 gram quantities, it will be apparent that a single determination often exhausts the sample.

Fourth, the adverse dilution factor. In prior gassing chambers the toxic agent and the diluting air are introduced and may be varied separately. Since the usual rate of air flow through the chamber is 250 liters a minute, the toxic agent must be introduced into the chamber at a concentration 250 times that of the desired final concentration. In order to achieve this high concentration it is often necessary to heat the bubbler which contains the toxic agent to a point where the volatility is at least 50 times that of the desired final concentration within the chamber. This procedure often results in the partial decomposition of the toxic agent before it can be tested.

Fifth, the admission of impurities. Since prior gassing procedures depend upon the vaporization of the toxic material by forcing nitrogen or air through a bubbler containing the material maintained at a constant temperature, it will be apparent that impurities of higher or lower vapor pressure present in the material to be tested will seriously affect the accuracy of the results obtained. In addition prior gassing chambers provide insufficient means to determine the vapor pressure and volatility of the compound necessary to secure the desired concentration of the agent in the chamber. Finally, it will be apparent that the introduction of mixtures of

two or more materials into prior chambers simultaneously is a cumbersome and unreliable procedure.

Sixth, the corrosion and deposition inescapable in the prior apparatus. The rate of air flow through prior art chambers is determined by means of an orifice meter. Corrosion of the orifice plate, or deposition of materials upon it tend to introduce serious errors in measurement of the rate of air flow through the chamber.

In the present invention a toxic liquid may be

2

displaced into an atomizer at any required rate, for example from 0.015 cc. to 21.4 cc. per minute. The rate of displacement depends upon the rate at which a piston is forced into a cylinder containing mercury. This piston speed is controlled by means of a change gear box. The atomized liquid is vaporized from a large surface by means of a warm air stream, and is then diluted with a carefully metered air stream before passing over the test animals. Because of its automatic nature the present apparatus permits testing of compounds at a speed hitherto unattainable. It has been found to be accurate, convenient, devoid of hazards, and well adapted to the study of mixtures of toxic compounds.

The principle of the apparatus 10 of the present invention is illustrated in the diagram in Fig. 1. For example, an 18 liter glass chamber into which the animals are inserted is shown at 42. Chamber 42 rests upon a glass plate 48 which serves as a floor. The chamber 42 can be raised from the glass floor 48 by appropriate hand lever operated rack and pinion means not shown, to permit insertion and removal of the animals to be exposed. A gastight seal is maintained by means of rubber gaskets 49. The chamber 42 is constructed with double walls shown at 47, and a suction of preferably 1½ inches of water is maintained at 46 between the walls 47 to prevent leakage of toxic material.

A constant and accurately metered rate of air flow, for example 180 liters per minute, is maintained through the chamber 42 by means of a metered air pump 15. This pump is operated through shaft 14 by positive gear box 12 from a synchronous motor 11 through connection 13. Motor 11 is also engaged through clutch 17 to gear box 18, shaft 19 to gear box 20, all of which control the delivery of the toxic fluid so that even if the motor 11 is not constant, the proportion of toxic agent to the total air remains constant.

The toxic liquid 100 is floated on a column of mercury 24 maintained in the burette assembly 26. One end of burette assembly 26 is connected to an atomizer 29 and on the other to a steel cylinder 23 containing mercury 24 as shown in Fig. 2. A stainless steel piston 22, preferably ½ or ¼ inch in diameter, fits into cylinder 23 and is tightly sealed with neoprene gaskets 66 so that no mercury leak can occur.

The piston 22 is attached to carriage assembly 21 and connected through gear box 20 to a compound set of adjustable gears 18 driven by motor 11 which also drives the metered air pump 15. The rate at which the piston 22 enters the cylinder 23 and causes mercury 24 to rise and displace the toxic liquid 100 into the atomizer 29 may be controlled by the adjustable gear box 18 in such a manner that more than 350 different rates are possible. The gears at 18 may be adjusted so that the piston 22 may be provided with a rate of travel ranging from 0.075 to 8.34 inches per minute. This range can, for example, be divided by proper adjustment of the gears at 18 into 385 separate steps. This makes it possible to select a gear setting such that the rate of delivery is usually the exact amount desired, and is always within 2% of the amount required. The threaded shaft 52 upon which the carriage 21 moves is preferably machined with 24 threads to the inch. Any appropriate table can be computed by well-known methods for providing the desired relationship of the gear settings at 18 to the distance which the piston 22 will be moved by the shaft 52 in a given time period. In order to displace a

given volume of material in a given time it is necessary only to refer to such a table to determine the proper gear settings in the table and adjust accordingly.

The main air stream at 35 is arranged so that 158 liters per minute go directly into the chamber 42, while 22 liters per minute enter a simple compressor indicated at 33 where it is compressed to provide a pressure ranging from 50 to 70 pounds. The compressed air may be heated by a suitable air heater at 31, used to atomize the liquid which has been forced into the atomizer assembly 29. The resulting spray is deposited in a fine film upon the interior wall of spiral condenser 36, which may be heated with steam or hot water introduced at 37, and is vaporized from the wall by means of the same air which has performed the atomization. The air containing toxic vapor 100 is then returned to the main air stream and passes through opening 41 over the animals in the glass chamber 42, leaving the chamber 42 through openings 43 and exit 45.

Illustrated in the lower portion of Fig. 2 is a front view of piston 22 and cylinder 23. The cylinder 23 is provided at its rearward end with a flange 93 and a compression plate 94 held to the flange 93 by bolts 65 or other suitable attaching means. Neoprene gaskets 66 are held between steel collars 67 around the piston 22 and within the cylinder 23 and are sealed in compression by tightening the plate 94.

The forward end of the cylinder 23 is provided with a flanged elbow member 68 to which is affixed the sealing clamp 69 by means of bolts 70 or other appropriate means. Lead gasket 71 and shellac seal 72 also helps to prevent leakage around the tube 27. The tube 27 is preferably 20-gauge stainless steel tubing and leads to the burette assembly 26 as shown in Fig. 1 and Fig. 2.

The burette assembly previously indicated by a front view at 26 in the overall diagram shown in Fig. 1, is shown in the upper portion of Fig. 2 by a rear view thereof. Assembly 26 is connected to the cylinder 23 by means of the stainless steel tubing 27 which is provided with the safety spring valve shown at 73 and with the 2-way stop cock 74 controlling the outlet 93 to a mercury reservoir. The 3-way stop cock shown at 75 may be preferably arranged to be electrically actuated by well-known solenoid means. Stop cock 77 which controls the release of mercury through the outlet 82 communicates with cock 75. Positioned above the outlet valve 77 is a graduated capillary member 81 leading to a well-known mercury-water interface arrangement in cylinder 78 which contains the mercury 24 and the contacting water 79.

As shown in the upper half of Fig. 2, the first mercury-water interface cylinder 78 communicates with the stop cock 80 which is used for evacuating the burette assembly 26 when it is being filled with mercury 24 and water 79. In this operation vacuum is applied through the stop cock 80 to remove all traces of compressible gas so that the entire system from the cylinder 23 to the atomizer assembly 29 contains non-compressible liquid.

The stop cock 80 is also connected with a second mercury-water interface cylinder 83 containing water at 78 and mercury at 24. The lower portion of cylinder 83 is in communication through tube 88 with the stop cock 75 and the stop cock 84. When stop cock 84 is turned 90° to the right the mercury 24 is withdrawn from the graduated cylinders 85 and 86 through the

outlet 87 which permits the toxic agent to be drawn into the burette assembly 26 through the conduit 28 from the atomizer assembly 29. The stop cock 84 is connected to the cylinders 85 and 86 by means of conduit 83. Cylinders 85 and 86 are provided with suitable graduations for measuring the amount of mercury to be displaced. This arrangement permits the toxic liquid 100 to be floated on the mercury 24 in cylinder 86 and its volume measured by displacement of the mercury as shown on the graduated scale on cylinders 85 and 86.

The 3-way stop cock 75 is shown in an operating position for a routine experiment. In this position mercury flows through the graduated capillary tube 81 and cylinders 86, 85, 83 and 78 displacing toxic agent 100 through the outlet tube 28 to the atomizer assembly 29. Before the starting contact for motor 11 is engaged, the by-pass 38 shown in Fig. 1 is opened and the stop cock 75 is turned 90° to the left. The mercury 24 then flows horizontally from stop cock 75 through conduit 89 and through open stop cock 84 to cylinders 85 and 86. In this way the relative positions of the mercury 24 and the water 79 in cylinders 78 and 83 are not disturbed until the starting contact for motor 11 is engaged. At the start of the test or experiment the mercury 24 is set at a given mark in capillary 81 and is returned to this mark at the end of the experiment by turning stop cock 84 to a neutral position, next opening stop cock 75 to the mercury reservoir 82 and withdrawing mercury by means of stop cock 77 until the original mark is reached on capillary 81.

In Fig. 3 the carriage assembly 21 includes the carriage gear box 20 arranged in operative relationship with the threaded shaft 52 for advancing the piston 22, and with the adjustable gear box 18 shown in Fig. 1. The threaded shaft 52 is preferably provided with 24 threads per inch. The accuracy of the machining can readily be tested by causing the piston 22 to be moved into the cylinder 23 for a given number of screw threads. This causes the mercury 24 to rise in the burette assembly 26. A mercury water interface is provided at 78 and at 83 in the burette 26 so that at the start the mercury 24 may be set at a given mark in graduated capillary 81. After the piston 22 has been moved forward, the mercury 24 can be withdrawn until it reaches the same given mark, and can then be weighed. It has never been found to differ more than 0.3% from the displacement calculated from the cross sectional area of the piston 22 and the distance it moves as measured by a suitable revolution counter 57 placed on the shaft 52 as shown in Fig. 3.

A table is available which relates the gear settings to the distance which the piston will move on the screw in a given time period. In order to displace a given volume of material in a given time it is necessary only to look up the proper gear settings in the table and adjust accordingly.

Referring again to Fig. 3, suitable clutch means 53 and 54 may be employed for releasing starting contact member 50 and stopping contact member 51 so that they may be set at any chosen distance apart on their respective shafts 60 and 61. Counter 55 is used for determining the setting of starting contact 50, and counter 56 is likewise used for stopping contact 51. Each number on counters 55 and 56 represents one-full turn of the threaded shaft 52. The numerical difference between the reading on counter 55 and that

on counter 56 represents the distance expressed in screw threads separating the starting and stopping contacts 50 and 51. Counter 57 counts the number of complete turns made by threaded shaft 52 and vernier counter 58 counts fractions of a turn made by shaft 52. At the beginning of the experiment the reading is noted on counters 57 and 58 and at the end of the experiment the reading on these counters 57 and 58 is again noted. The numerical difference between these two readings represents the exact number of threads (on shaft 52) which piston 22 has moved forward during the experiment. From this distance the exact volume of toxic fluid 100 displaced by mercury 24 through tube 28 may be readily computed by means of the various tables referred to herein.

Control mechanism

Fig. 2 illustrates in perspective a skeleton view of a front elevation of a part of the carriage assembly 21. (The carriage 21 as diagrammed in Fig. 1 shows a top view representation of members 50 and 51 to clarify that part of Fig. 1.) It includes the end support members 91 and 92 and longitudinal support members 95. The main threaded shaft 52 is driven through change gear box 20 by means of a system of gears which rotates a nut that is in engagement with shaft 52 and thereby causes shaft 52 and carriage 21 to travel longitudinally in a forward and rearward direction in a manner well-known in the mechanical arts. The piston 22 preferably has a suitable floating bearing connection with end support 92 so that maximum accuracy may be assured by causing the piston 22 to be independently rotated on its longitudinal axis during its longitudinal advance against the column of mercury 24 in the cylinder 23. This is accomplished by means of the pinion 64 attached to piston 22 and engaging driving gear 63. Drive gear 63 is rotated by the driving shaft 59 from the independent driving motor 62. Shaft 52 is provided with a suitable revolution counter 57 cooperating with a vernier counter 58 for indicating fractions of a revolution, so that the exact distance of travel of piston 22 may be accurately indicated.

Suitably mounted in the end supports 91 and 92 are the threaded shaft 60 used for "starting" control, and the threaded shaft 61 used for "stopping" control. Both of these shafts have the identical number of threads per inch, preferably 24, that are provided in shaft 52. Threaded shafts 60 and 61 are provided with revolution counters 55 and 56, respectively, for setting members 50 and 51 on shafts 60 and 61 at their chosen positions. Trip members 51 and 50 are in threaded engagement with the threaded shafts 61 and 60, respectively. Members 50 and 51 travel with carriage 21. When member 50 reaches the end of its travel, it is arranged to actuate a starting solenoid switch lever and in a like manner trip member 51 when it reaches the end of its concurrent travel with carriage 21, it is arranged to actuate a stopping solenoid switch lever. These switch levers are independently supported in appropriate positions adjacent carriage 21, and each lever provides an on and off connection between a source of electricity and a series of servo-motors. These servo-motors, when energized, are arranged to respectively actuate components of the apparatus of the present invention in the following manner.

The 3-way valve at 75 is actuated by a servo-

motor; the clutch at 17 is actuated by a servo-motor; and the by-pass valve at 38 is also servo-motor operated. The compressor switch at 33, the meter switch at 15 and the servo-motor switches are arranged to be energized after contact members 50 and 51 are set at the desired positions. Each of these members is arranged to actuate a well-known micro-switch which in turn concurrently actuates clutch 17, and 3-way valve 15, in a manner well-known to those skilled in the art of servo-motors.

Referring to Fig. 2; before beginning the operation it is necessary to turn the 3-way stopcock, at 84, 90° to the right so that the mercury 24 is withdrawn from cylinders 85 and 86. This causes the toxic agent 100 to be drawn into the burette 26 through conduit 28. Next, the stopcock 84 is returned to its closed position. Subsequently, gear box 18 is set for the desired cycle. Next, chamber 42 is elevated and the animals inserted therein, then lowered and the suction seal between the double walls 49 is reestablished at 46. Next, the mercury 24 is set at the desired mark in capillary 81. At the end of the experiment, mercury 24 may be returned to this position by turning stopcock 84 to a neutral position and opening stopcock 75.

In order to test a substance for toxicity at the screening level of 3.0 mg., the density of the substance 100 must be known, and some knowledge of the vapor pressure is desirable in order to determine whether the air used for atomization should be heated by heater 31 and the walls of the spiral condenser 39 should be heated by circulating hot water at 37 in order to secure vaporization of the compound. From the density, the volume of liquid per minute to be displaced into the atomizer 29 may be calculated. The proper gear settings, determined from the table, are made and the burette 26 is then loaded with toxic liquid 100 by withdrawing the mercury 24. The automatic start and stop members 50 and 51 are set ten minutes apart and the air compressor 33 is set into operation. The animals are placed in the chamber 42 and the main switch, starting the blower 15, is actuated. The clutch 17, connecting the change gear box 18 with gear box 12 and the motor 11, is engaged causing the carriage 21 to move forward, the piston 22 to move into the cylinder 23 and the toxic liquid to be displaced in the atomizer 29. The by-pass valve 38, which is connected to a vacuum or source of suction such as the exhaust stack, is open during this period, so toxic vapor does not pass into the main air stream at 41 going to the animals but bypasses chamber 42 and leaves the system completely, ultimately going into the exhaust system of the laboratory. However, when the carriage 21 has moved forward sufficiently it causes the starting member 50 to energize the switch actuated servo-motor operated valve at 38. This causes the by-pass valve 38 to close automatically, and the toxic material then enters the main air stream at 41 going to the animals in chamber 42. After ten minutes the stopping member 51 is engaged. This reopens by-pass valve 38 and simultaneously releases the clutch 17, similarly servo-motor operated, so that the delivery of toxic liquid 100 is terminated. The blower 15 is continued during this period so that the chamber is quickly purged. The chamber 42 is then lifted from the glass floor 48, the animals are removed. Only a different gear setting in change gear box 18 is required to repeat the exposure just described for a different time or with a different

concentration, or different toxic material, or different mixtures of materials.

Conclusion

In contrast to prior procedure with former apparatus, the experimental animals are inserted in the chamber 42 of the present invention, before the toxic material 100 enters the chamber 42 and are withdrawn after the chamber 42 has been cleared.

The accuracy of the technique and apparatus of the present invention has been tested biologically and chemically with a wide variety of compounds. Analytical samples were taken at the vent 45 illustrated in Fig. 1. As described herein, nominal concentrations determined either by calculation from the diameter of the piston and the distance it moves, or by determination of the weight of mercury displaced invariably agree within 0.3%. With propionic acid, the analytical nominal ratio was of the order of 1, and with diphosgene, the analytical nominal ratio was of the order of 0.95.

The advantages of the present apparatus have overcome the objections inherent in prior disclosures, as set forth herein. The saving of time by the present invention is most important, because at least five times as many compounds can be tested in a day as is possible with prior apparatus. In the screening of compounds, where nominal concentrations are employed, the accuracy is greater than formerly taught because the well-known objectionable wall effects are at a minimum in an all glass apparatus. Furthermore, the material is volatilized in $\frac{1}{5}$ the total air flow in the present apparatus, while in former chambers not more than $\frac{1}{25}$ of the total air flow can be used. This means that substances of low volatility can be vaporized at lower temperatures than in the past, and decomposition is much less likely.

In addition to the greater speed and accuracy, the present invention requires less material for testing, and is much less hazardous to operate than the standard chamber. Furthermore, the present invention permits the dispersing of two or more toxic agents simultaneously. Since the delivery is quite independent of the vapor pressure of the substance under examination, mixtures of many materials of various vapor pressures may easily be tested in the improved apparatus described herein.

The herein described illustration of the present invention shows the gear box assemblies at 18 and at 12; the motor drive assembly at 11, and the gas chamber assembly at 42, incorporated as part of the entire apparatus 10 as shown in Fig. 1. However the present invention operates very successfully as a portable unit adapted to separately engage a series of gas chambers in succession by providing suitable connections at 41 and 43 (not shown) for attachment to standard connections on each chamber in a series.

Furthermore, additional standard connections can be provided at shaft 14 and at shaft 19 if desired so that any one of an appropriate series of gear boxes and motor drives may be used with the present invention whenever desired.

While applicant has herein described his improved testing apparatus and procedure in detail with respect to a preferred embodiment thereof, he does not contemplate limitation thereto, but does include all forms and modifications thereof within the spirit and scope of the appended claims.

I claim:

1. The method of determining the toxicity of a liquid that includes the following steps: atomizing said liquid, heating said atomized liquid to form a vapor, volumetrically controlling the dilution of said vapor with air and passing said diluted vapor at a controlled rate through a sealed chamber containing animal life.

2. The method of determining the toxicity of a liquid that includes the following steps: atomizing said liquid, heating said atomized liquid to form a vapor, volumetrically controlling the dilution of said vapor with another vapor, and passing said mixed vapors at a controlled rate through a sealed chamber containing animal life.

3. The method of determining the toxicity of a liquid that includes the following steps: atomizing said liquid, heating said atomized liquid to form a vapor, volumetrically controlling the dilution of said vapor with another vapor and with air, and passing said mixture at a controlled rate through a sealed chamber containing animal life.

4. Apparatus for determining toxicity, comprising in combination: a sealed exposure chamber, a conduit therethrough, propulsion means for maintaining a controlled metered stream of air through said conduit and said chamber, means for diverting a portion of said air at a diversion point in said conduit before said air reaches said chamber, means for compressing said diverted

air, means for heating said compressed air, atomizer means in communication with said compressing means, displacement means arranged to provide a controlled metered flow of liquid to said atomizing means; selective power transmission means in operative relationship with said displacement means and with said propulsion means, power means for driving said transmission means; vaporizing means in communication with said atomizing means, heating means in communication with said vaporizing means, means for returning a controlled metered flow of the resulting mixture of said diverted air and said vapor into said stream at a point between said chamber and said diversion point, and means for exhausting said stream into the atmosphere after it has passed through said chamber.

MATTHEW EDWARD BENESH.
